UNITED STATES PATENT OFFICE.

VILETTA A. BROUILLET, OF SAN LUIS OBISPO, CALIFORNIA.

SPOOL-HOLDER.

1,215,476.

Specification of Letters Patent. Patented Feb. 13, 1917.

Application filed December 27, 1915. Serial No. 68,766.

To all whom it may concern:

Be it known that I, VILETTA A. BROUILLET, a citizen of the United States, residing at San Luis Obispo, in the county of

5 San Luis Obispo and State of California, have invented certain new and useful Improvements in Spool-Holders, of which the following is a specification, reference being had to the accompanying drawings.

10 My invention relates to devices for supporting articles, and particularly to a device for supporting spools of thread.

The primary object of my invention is the provision of a very simple device adapted 15 to support a plurality of spools of thread, so constructed that the spools may be easily placed upon or removed from the device and the thread unwound from the spools.

A further object of the invention is the 20 provision of a device of this character which may be very cheaply constructed and in which the spool engaging and supporting members may be readily made and assembled with the base.

25 A further object of the invention is to so construct the device that the spool supporting members when engaged with the base will be held rigid in position.

Still another object of the invention is 30 to provide a device of this character in which the spool supporting members may be readily detachable from the base so that they may be laid flat against the base for compact packaging.

35 Other objects will appear in the course of the following description.

My invention is illustrated in the accompanying drawings, wherein:

Figure 1 is a face view of the complete 40 spool supporting device;

Fig. 2 is a perspective view of a portion of the base and showing one of the spool supporting members in position;

Fig. 3 is a vertical section on the line 3—3 45 of Fig. 2;

Fig. 4 is a fragmentary face view of the plate 10;

Fig. 5 is a side elevation of one of the supporting members 13 detached from the 50 plate.

Referring to these drawings, 10 designates a sheet of relatively thin metal which may be of any desired ornamental character and which is preferably provided with 55 a bead 11 at its edges to strengthen it. At its upper end the sheet is formed with an

opening 12 whereby it may be supported upon a nail. This plate or sheet 10 forms the base upon which the spool supporting members 13 are mounted.

The plate 10 is formed with a series of perforations 14 and 15 arranged in transverse series across the plate, the perforations 14 being in staggered relation to the perforations 15. The material of the plate 35 above each perforation 14 is outwardly pressed, as at 16, while the material of the plate below each perforation 15 is outwardly pressed, as at 17. These outwardly 40 pressed portions 16 and 17 extend longitudinally of the plate and form a plurality of pairs of seats, the seats of each pair being in staggered relation, as shown clearly in Fig. 2. Below each perforation 14 the metal 45 of the plate is slightly depressed toward the back of the plate, as at 18, and above each perforation 15 the metal of the plate is slightly depressed toward the back, as at 19.

The spool supporting members 13, as illustrated most clearly in Figs. 2 and 3, are 50 each formed of a single piece of wire. The length of the wire is bent at its middle, as at 20, and the two legs of the wire thus formed are extended parallel to each other, as at 21, and are then angularly bent to 55 provide portions 22 which extend in rearwardly divergent relation to each other and then the extremities of these portions 22 are angularly bent as at 23 and 24, the portion 23 being bent upward and the portion 24 60 being bent downward or in reverse direction to the portion 23. Preferably the upper end of the spool support at 20 is slightly enlarged.

As illustrated clearly in Figs. 2 and 3, 65 each spool support is engaged with the base plate by inserting the leg 23 through the perforation 14 and the leg 24 through the perforation 15. This may be easily done 70 by inserting the portion 23, for instance, in the perforation 14 and then shifting the spool support upward until the extremity of the portion 24 can be inserted within the 75 opening 15. The support is then shifted downward until the portion 24 bears firmly 80 upon the lower end of the seat 17. Because 85 of the fact that the portions 22 of the support are in divergent relation to each other, no rotation of the spool support is possible 90 upon the base and as the portions 23 and 24 95 extend in opposite directions and each of the portions 23 and 24 bears partly against 100 105 110

the front of the plate and partly against the back of the plate the spool support is held rigidly in place. The spool supports may, however, be readily detachable by reversing 5 the operation previously described.

In the use of my device spools are placed upon the several spool supports and the thread may be drawn from the spools as needed. The enlarged upper end of the 10 spool support has sufficient frictional engagement with the spool as to prevent its accidental rotation but not such as to prevent the thread from being readily drawn off from the spool. The end portions 23 and 15 24, as will be seen from Fig. 3, are not exactly at right angles to the portions 22 but at less than a right angle to these portions so that when the portions 23 and 24 are inserted within the seats 16 and 17 they 20 will firmly engage therewith and clamp against the plate.

It will be seen that my device is very handy and convenient, that it is very cheap to make, and that the spool supports may 25 be readily detached from the base so that they can be placed in a small box for transportation. While I particularly advise this construction for supporting spools, I wish it understood that the same principle might 30 be applied for the support of other objects.

Having described my invention, what I claim is:

1. A spool support of the character described including a plate having a pair of 35 perforations spaced from each other, and a supporting member having angularly and oppositely extending extremities inserted through said perforations, said angularly extending extremities bearing partly against 40 the back of the plate and partly against the front of the plate whereby to prevent movement of the supporting member at right angles to the face of the plate.

2. A spool support of the character described including a plate having a pair of 45 perforations spaced from each other both laterally and longitudinally, and a supporting member having legs divergently inclined with respect to each other and extending in 50 ward toward the face of the plate, said legs being formed with angular extremities extending in opposite directions, one of said extremities inserted through one of said perforations and the other through the 55 other perforation.

3. A support of the character described including a plate having a pair of perforations, the metal of the plate on one side of one perforation and the opposite side of the

other perforation being outwardly pressed 60 to form longitudinally extending seats, and a supporting member having angular extremities extending in opposite directions to each other, said extremities being longer than the seats and inserted through said 65 perforations and bearing partly against the inside faces of said seats and partly against the front of the plate.

4. A supporting device of the character described including a plate having a pair of 70 perforations in it, the metal of the plate on one side of one perforation and the opposite side of the other perforation being outwardly pressed to form longitudinally 75 extending seats, said perforations of the seats being out of alinement with each other, and a supporting member having angular extremities extending in opposite directions and also disposed out of alinement with each other, said extremities being 80 insertible through said perforations and bearing partly against the front face of the plate and partly against the rear faces of said seats.

5. A device of the character described including a plate having a pair of perforations formed in the plate, the perforations being out of alinement with each other, the metal of the plate on one side of one perforation and on the other side of the other 90 perforation being outwardly pressed whereby to form longitudinally extending seats, and a supporting member formed of a single piece of wire bent upon itself, the legs so formed being angularly bent at their ends 95 with relation to the body of the wire and in divergent relation to each other, the extremities of said angularly bent legs being angularly bent in opposite directions and parallel to the body of the wire for reception 100 each in one of said seats.

6. A supporting device of the character described including a plate outwardly pressed to form longitudinally extending seats on the inner face of the plate spaced 105 from each other and disposed out of alinement, the seats opening toward each other, and a supporting member having divergent legs, the extremities of the legs being angularly bent in opposite directions but parallel 110 to each other and being disposed in said seats.

In testimony whereof I hereunto affix my signature in the presence of two witnesses.

VILETTA A. BROUILLET.
